[57] CLAIM

The ornamental design for a base for newspaper vending machine, substantially as shown and described.

DESCRIPTION

FIG. 1 is a top front perspective view of a base for newspaper vending machine showing my new design;

FIG. 2 is a left side elevational view thereof, the right side being a mirror image thereof;

FIG. 3 is a top plan view thereof;

FIG. 4 is a front elevational view thereof, the rear view being a mirror image thereof; and

FIG. 5 is a bottom plan view thereof.

The views opposite to those illustrated in FIGS. 2 and 4 are mirror images of those illustrated in FIGS. 2 and 4.
